CAN PUNCTURING DEVICE

Harvey Geipel, Milwaukee, Wis.

Application December 16, 1952, Serial No. 326,190

4 Claims. (Cl. 30—6.1)

1.

My invention relates to a can puncturing device and more particularly to a device for cutting a pouring spout and piercing a ventilating aperture in the top of a tin can.

The object of my invention is to provide a device that may be mounted onto a permanent support so that it is accessible and convenient for the user.

Another object of my invention is to construct a device in such a manner that varied sizes of cans may be accommodated without any mechanical changes.

A still further object of my invention is to provide a device of the character described, in which the piercing unit may be slidably adjusted within the handle, to vary the distance between the cut spout and the pierced ventilating aperture in the can.

A still further object of my invention is to provide a device that may be easily manufactured, easily manipulated, yet be highly efficient for the purpose for which it is intended.

It is manifest to anyone familiar with the art, that a housewife or the like quite frequently needs to puncture cans of varied sizes in the preparation of food, and in the practice of the culinary art, it is very inconvenient to be compelled to use varied devices for this purpose, and it is the purpose of my invention to provide a single device that may be easily adjusted and that will accommodate the various sizes of cans without any mechanical adjustment.

Other and further objects of my invention will become more apparent as the description proceeds when taken in conjunction with the drawings, in which

Figure 1 is a perspective view of my assembled device, in which the body of the device is serrated and bent into a series of steps or ledges.

Figure 2 is a side view of the device as shown in Figure 1, attached to a permanent vertical member and showing various sizes of cans in dotted lines.

Figure 3 is a longitudinal cross-sectional view of the lever portion, showing the arrangement of the cutting blade and puncturing device on the handle, and

Figure 4 is a fragmentary perspective view of a portion of the body, in which the step portions are stamped out and bent at an angle, as an integral unit of the body portion.

Similar characters of reference indicate corresponding parts throughout the several views and referring now to the same, the character 10 shows a body portion which is constructed of a piece

2.

of band metal. It is provided with an angularly disposed section formed into a plurality of steps shown as 11, and has at its top, a projecting ledge 12 to accommodate the side of the can being punctured. There are two flat sections on the body 10. These sections are indicated by 13 at the top and 13' at the bottom and permit the attachment of the body of the device by means of screws or the like engaging apertures shown as 14 through the flat portions 13 and 13'. There is also a pair of top guides shown as 15, which are integrally constructed and project outward from the flat portion 13 in the body of the device, and act as a top guide for the can being punctured.

The body portion 10 is provided at the top with formed sections 16 and 16' which produce cylindrical sleeves through which a pin 25 is disposed, and the handle portion 18 is provided also with a similar cylindrical sleeve shown as 17 which encircles the pin 25 and provides a hinged attachment for the handle portion 18.

There is a cutting blade shown as 19 which is integrally formed and cut out at its one edge from the handle 18. This blade is radially disposed and projects downward providing a pointed section 20 on the extreme edge of the blade 19.

The handle 18 is further provided with an elongated slot shown as 21 into which is mounted a piercing unit consisting of a top portion 22 and a pointed bottom portion 23. The head or top portion 22 provides a means for the user to manipulate and slidably move the piercing assembly within the slot 21, to vary the distance between the point 20 of the blade 19 and the piercing unit 23.

There are screws 24 shown in Figure 2 disposed within the apertures 14. These screws 24 act as a mounting for the entire body.

The cans are shown in phantom that is in dotted lines in Figure 2, which show a small can 28 being brought into contact at the point 26 with the outwardly projecting ledge 12 and resting on the top step portion 11 at 27, while the larger can shown in phantom as 29 rests on the step 11 at the point shown as 27'. This arrangement provides support for the various size cans, and as shown in Figure 2, in phantom, the lever is raised and the piercing point 23 is moved to accommodate the particular size of can that is being pierced. In both cases, no matter what the size of the can would be, the can as indicated in Figure 2, and the step 11, which step obviously may be of any conventional design, and as a modification, I show in Figure 4, steps 31 pro-

jecting outward from the outer face of the angular portion body 10.

In operation, the device is exceedingly simple to manipulate inasmuch as a can is placed onto one of the steps 11 as shown, with the top portion of the can contacting the lower face 30 of the top guide 15, and the side of the can contacting the projecting ledge 12 as shown at 26. Depending on the diameter of the can, the top 22 of the slideable puncturing member may be adjustably and slideably moved within the slot 21 bringing the piercing point 23 towards or away from the point 20 of the shearing blade 19 and in this manner a simple movement of the handle portion 18 downward will cut a pouring spout through the top of the can and will also cause the piercing point 23 to enter the top of the can, and while I have herein shown a specific structure of my device and the arrangement of the component parts constituting my invention, I am fully cognizant of the fact that many changes in the form and configuration of the parts may be made without affecting their function, or without departing from the spirit of my invention, or the scope of the appended claims.

Having thus described my invention, what I claim and desire to secure by Letters Patent in the United States is:

1. A device of the character described comprising, a body portion and a handle portion, said handle portion hingedly attached to the upper end of said body portion, a cutting blade, said cutting blade being integral with and extending outward from, the bottom of said handle near the hinged attachment, a piercing member, said handle provided with a longitudinal slot extending therethrough, said piercing member slideably mounted within said slot and extending outward from its lower face, said body having an angularly disposed portion provided with a plurality of steps integrally formed therein, said body having apertures extending therethrough, to accommodate means for attaching said body to a fixed mounting.

2. A device of the character described, comprising, a body portion and a handle portion, said handle portion hingedly attached to the upper end of said body portion, a flat upper and lower portion on said body, said flat portion provided with apertures to accommodate attaching means for attaching said body to a fixed mounting, the upper end of said body portion provided

with an outwardly extending contact, an angularly disposed portion below said contact, said angularly disposed portion provided with a plurality of steps extending across the front of said body, said handle portion provided with a cutting blade near its hinged attachment to said body, said cutting blade being formed integral with said handle and having a point extending downward from the lower face of said handle, a piercing member, said handle provided with a longitudinal slot, said piercing member slideably mounted within said slot for moving same and thereby varying the distance between said piercing member and the cutting blade.

15 3. A device of the character described, comprising a body and a handle portion hingedly attached to one another at one end, a flat mounting portion at the top and lower end of said body portion, an angularly disposed portion located between the upper and lower flat body portion, an outwardly extending contact edge integrally formed with said body above said angular portion, outwardly extending top guides formed at right angle to the upper front portion 20 of said body, a cutting blade integral with said handle, said handle being provided with a longitudinal slot, a piercing member slideably supported within said slot and means for attaching said body portion to a fixed mounting.

25 4. A device of the character described comprising, a body portion and a handle portion, said handle hingedly attached to the upper end of said body, a vertical flat section on said body, said flat section provided with apertures, the upper end of said body having outwardly extending members provided with downwardly disposed sections, the vertical flat section of said body provided with a plurality of step members, said handle portion provided with a cutting blade near its hinged attachment to said body, said cutting blade extending downward from the lower face of said handle, a piercing member, said piercing member slideably supported by said handle and extending downward therefrom.
